NEUROLOGICAL PERCUSSION HAMMER OR THE LIKE

Clayton A. Laughlin, Minneapolis, Minn., assignor to
Arthur Salm, Inc., Chicago, Ill., a corporation of
Illinois

Filed Aug. 5, 1965, Ser. No. 86,465

Term of patent 14 years

(Cl. D83—12)

FIG. 1 is a perspective view of a neurological percussion hammer showing my new design;

FIG. 2 is a top plan view thereof;

FIG. 3 is a front elevational view thereof;

FIG. 4 is a rear elevational view thereof;

FIG. 5 is an end view thereof showing the handle end;

FIG. 6 is a reduced top plan view corresponding to

FIG. 2 with the handle in the extended position;

FIG. 7 is a reduced top plan view corresponding to

FIG. 2 with the handle extended and the head pivoted to the operational position; and

FIG. 8 is an exploded fragmentary view of the head portion of the percussion hammer of FIG. 1 showing in broken lines the point and brush which are stored within the head.

The showing of the point and brush in dotted lines is for illustrative purposes only.

I claim:

The ornamental design for a neurological percussion hammer or the like, substantially as shown and described.
